UNITED STATES PATENT OFFICE.

JAMES B. HOOPER, OF MELROSE, MASSACHUSETTS.

FASTENER FOR SHOE-LACES.

SPECIFICATION forming part of Letters Patent No. 678,107, dated July 9, 1901.

Application filed March 26, 1901. Serial No. 52,928. (No model.)

To all whom it may concern:

Be it known that I, JAMES B. HOOPER, a citizen of the United States, and a resident of Melrose, county of Middlesex, and State of Massachusetts, have invented an Improvement in Fasteners for Strings, Shoe-Laces, &c., of which the following description, in connection with the accompanying drawings, is a specification, like letters on the drawings representing like parts.

This invention has for its object the production of a simple, cheap, and effective device of novel construction for fastening or holding in place the free or loose end of a shoe-lace, glove, or corset-string without the aid of knots or enlargements in the lace or string.

The fastener can be readily applied to the shoe-upper or other analogous article, and coöperates preferably with the endmost eyelet of the series through which the lace passes.

Figure 1 is an inner side view of the front flaps of a shoe-upper or other analogous article with one embodiment of my invention applied thereto. Fig. 2 is a longitudinal sectional view through the fabric and the attached fastener, the latter being shown in locking position. Fig. 3 is a like view, but with the fastener unlocked to release the lace or string. Fig. 4 is a view of a modified form of fastener in use, and Fig. 5 is a longitudinal section thereof.

Referring to Figs. 1, 2, and 3, the fastener consists of a thin flat metallic plate or body a , preferably decreasing in width toward one end and having projecting therefrom at its under side or face a rigid locking-prong a' , preferably made slightly tapering or frustoconical, as shown in Figs. 2 and 3. The larger end a^2 of the body has a hole a^3 therein to receive an eyelet e , of usual construction, by means of which the body is secured to the supporting fabric.

In Fig. 1 I have shown the upper ends of the front flaps $F F'$ of a shoe-upper each provided with a series of lacing-eyelets, through which the lace b^x is passed, a single lace being shown. The fastener is applied to the inner side of one of the flaps, as F , in such a position that the prong a' is opposite the endmost eyelet f of the series and the attaching-

eyelet e may conveniently be the next eyelet of such series. The free end of the lace is passed through the eyelet f from the outside and when drawn properly taut the free end of the fastener-body a is pressed against the flap F to force the prong a' into the eyelet f , clamping or wedging the lace tightly therein, as in Fig. 2. Manifestly strain on the lace will only serve to more firmly wedge the prong and the lace into the eyelet, while to release the lace a pull on its free end instantly withdraws the prong, as in Fig. 3, the resiliency of the body a permitting such withdrawal. It will be noticed that when the fastener is in use it lies perfectly flat against the flap and presents no obstruction or enlargement to annoy the wearer of the shoe. If desired, the attached end of the fastener-body may be inserted beneath the lining m through a slit m^x , Fig. 1, and the breadth of the body as it rests against the supporting fabric provides for a firm support. To apply the fastener to a completed shoe, the second eyelet from the end of the series can be removed and replaced by the attaching-eyelet e , or a smaller eyelet may be used to attach the fastener, such eyelet passing through one of the eyelets of the series.

In Figs. 4 and 5 I have shown a modification wherein the thin flat resilient body d has at its free end the locking-prong d' , as before; but the opposite end is sharpened to form an attaching-prong d^2 , which is pressed into the supporting fabric F^x and clenched, and at or near the middle of the body a second pointed attaching-prong d^3 is struck up, said prong d^3 passing through the fabric and being clenched oppositely to the prong d^2 . In this case the fastener is so located that its locking-prong d' will be in position to enter the lace-eyelet f^x to clamp the lace b therein.

The fastener may be used on shoes, gloves, corsets, or other articles wherein a fastening string or lace is employed, and it may also be used in connection with a bag-tie, as will be readily understood.

The fastener is exceedingly simple in construction, and it can be easily and cheaply made. As it has no joints, hinges, or other relatively movable parts, it is very strong and durable and cannot get out of order.

Having fully described my invention, what I claim as new, and desire to secure by Letters Patent, is—

1. A fastener for shoe-laces and the like, comprising a flat resilient metallic body adapted to rest at one end directly upon the shoe-upper or analogous article, and having at its free end a locking-prong projecting from its under side and adapted to enter an ordinary lacing-eyelet and clamp or wedge therein the lace or string passed therethrough, and means independent of the said eyelet for securing the end of the body directly to the shoe-upper or analogous article.
- 15 2. A fastener for shoe-laces and the like, comprising a flat resilient metallic body adapted to rest at one end directly upon the shoe-upper or analogous article, and having at its

free end a locking-prong projecting from its under side and adapted to enter an ordinary lacing-eyelet and clamp or wedge therein the lace or string passed therethrough, and means independent of the said eyelet for securing the end of the body directly to the shoe-upper or analogous article, said means comprising prongs integral with the said metallic body and adapted to enter and be clenched in the fabric to which the fastener is applied.

In testimony whereof I have signed my name to this specification in the presence of two subscribing witnesses.

JAMES B. HOOPER.
